UNITED STATES PATENT OFFICE.

BARDWELL A. GOODELL, OF WALTHAM, MASSACHUSETTS.

DESIGN FOR WATCH-HANDS.

Specification forming part of Design No. 6,698, dated June 3, 1873; application filed May 24, 1873.

To all whom it may concern:

Be it known that I, BARDWELL A. GOODELL, of Waltham, in the county of Middlesex and State of Massachusetts, have invented a new and original Design for a Watch-Hand, of which the following is a specification:

The accompanying drawing fully represents my improved design which consists of a half circle, *a*, cross *b*, and wedge-shaped part *d*, arranged on a watch-hand, as shown.

I claim as my invention—
The design for a watch-hand, substantially as set forth and shown.

BARDWELL A. GOODELL.
